UNITED STATES PATENT OFFICE.

JOSEPH BEAUDRY, OF WATERVILLE, MAINE.

DRILLING-MACHINE.

1,272,345.

Specification of Letters Patent.

Patented July 9, 1918.

Application filed January 15, 1916, Serial No. 72,318. Renewed April 7, 1917. Serial No. 160,544.

To all whom it may concern:

Be it known that I, JOSEPH BEAUDRY, a subject of the King of Great Britain, residing at Waterville, in the county of Kennebec 5 and State of Maine, have invented certain new and useful Improvements in Drilling-Machines, of which the following is a specification.

An object of my invention is to provide a 10 drilling machine which is so constructed that the drill is given reciprocatory movement in the operation, and the parts actuating the drill may be driven by a gasoline engine, an electric motor, or other light 15 power means, thus making the machine readily portable.

A further object is to so construct the means by which the drill is held and operated that the drill may be raised and lowered 20 at the will of the operator while the machine is in action or when the parts are idle.

With the above and other objects in view, my invention consists in certain novel features of construction and combinations of 25 parts which will be hereinafter set forth in connection with the accompanying drawings and then more particularly pointed out in the claims.

In the drawings:—

30 Figure 1 is a view in side elevation of the operating mechanism of my invention.

Fig. 2 is a view in front elevation.

Fig. 3 is a view in rear elevation of the machine.

35 Fig. 4 is a detail view of the drill operating lever.

The base 1 of the machine may be mounted on wheels, on runners, or may be constructed to be placed directly upon the 40 ground or rock into which the drill is to be sunk.

A supporting standard 2 is mounted on the base and at its upper end has the arm 3 disposed at right angles to overhang the base 1, this arm being preferably supported by the brace member 4 to have additional strength. A frame member 5 is connected with the standard 2 at a point above the base 1 and the brace 6 and the upright 7 are provided to mount this frame member 5 in a 45 rigid relation with respect to the standard 2 and the base 1.

50 A power shaft 8 is mounted across the standard 2 near the lower end thereof and at

one end has the loose and tight pulleys 9 and 10, a belt 11 being led from any suitable source of power, which might be an explosive engine, an electric motor, or other suitable driving means, to be looped over these pulleys 9 and 10, the belt shifter 12 being provided to move the belt to either of its driving positions. At a point above the mounting of the power shaft 8, bearings 13 are provided and the operating lever 14 is extended between these bearings and is pivotally mounted therein by the pins 15 so that the operating lever may have rocking movement.

The outer end of arm 3 is bifurcated as at 16 and a hand wheel 17 is mounted in this bifurcated portion to be capable of turning movement on a vertical axis and is provided in its center with a polygonal shaped socket. A drill supporting member 18 is cored out to receive the drill 19 and the polygonal shaped extension 20 is passed up through the socket of the hand wheel 17 so that this drill carrying member 18 is mounted in such a relation that the drill 19 will be vertically disposed, the connection through the hand wheel 17 being sufficiently loose that the parts may be capable of reciprocatory movement. The drill carrying member 18 is slit at its lower end to form a clamping portion or chuck 21, and the U-shaped clamp bolt 22 being provided to tighten this clamp portion against the sides of the drill 19 to hold the drill in a predetermined extension from the carrying member 18. The drill carrying member is 90 made of a considerable longitudinal extent and in the upper portion is cylindrical, this cylindrical portion being screw-threaded as at 23 and the feed nut 24 being received on this screw-threaded portion. This feed nut 95 is notched out at each side as at 25 and the fork arms 26 are secured on the forward arm of the operating lever 14 to be received in these notched openings 25 of the feed nut 24 so that as the operating lever 100 14 may be given rocking movement around its pivotal mounting in the bearing 13, reciprocatory movement in a vertical path will be transmitted to the drill carrying member 18 and consequently to the drill 19, 105 the extension 20 being moved slidably through the socket of the hand wheel 17.

An operating shaft 28 is mounted on the

frame member 5 at a point adjacent the free end of the operating lever 14, and a belt wheel 29 thereon has the belt 30 looped thereover and around the drive pulley 31 on the power shaft 8, so that as the belt shifter 12 may be moved to bring the belt onto the pulley 10 and motion is given to the power shaft 8, the operating shaft 28 will be turned. A coil spring 32 is connected between the forward arm of the operating lever 14 and the base 1 to normally exert a tension to draw this end of the arm downwardly, and to counteract this action of the spring, and to accomplish the desired reciprocatory movement of the drill and the hammer driving action, a cam 33 is secured on the operating shaft 28 in line with the free arm of the operating lever 14, this cam being arranged on its one face to have a gradual rise and then cut off sharply so that as the operating shaft 28 is turned in the direction of the arrow in Fig. 1, the operating lever 14 will be swung to raise the drill against the tension exerted by the spring 32 and as the cam has passed its highest point of lift, the operating lever is generally released and the spring 32 is then free to contract and to draw the operating lever down sharply to accomplish the driving blow of the drill. To insure a prompt return movement of the operating lever under the action of the spring 32, it is perhaps preferable that the cam engaging end of the operating lever 14 be formed in a gradual curve as at 34 and thus the release by the cam will be even more sharp and will be practically instantaneous.

When the parts are in operation and it is desired to turn the drill to loosen the same or to prevent wedging, this may be accomplished by giving turning movement to the hand wheel 17 and through the extension 20, this movement will be imparted to the drill to cause the cutting end thereof to be shifted in torsional movement. By continuing this same turning of the hand wheel 17 in one direction or the other, the drill carrying member 18 will have the threaded portion thereof fed through the feed nut 24 and in consequence the drill will be either raised or lowered as may be desired, this action being possible either during the operation of the parts or when the driving belt has been shifted to the loose pulley and the parts are consequently still.

While I have herein shown and described one specific form of the invention, it will be understood that various modifications in the form and arrangement of the parts can be made, that the base might be mounted on wheels, or runners to permit more ready transportation of the same, and that other modifications can be resorted to without departing from the spirit and scope of my invention, and hence, I do not wish to be limited

to the exact disclosure, but only to such points as may be set forth in the claims.

I claim:

1. A drilling machine comprising an upright having an arm disposed to extend therefrom and provided at its outer end with a bifurcated opening, a drill carrier mounted in conjunction with said arm to be capable of vertical reciprocatory movement, a feed nut received around said drill carrier, an operating lever pivotally mounted on the upright standard to be capable of swinging movement and connected with the feed nut to transmit reciprocatory movement thereto as the lever is swung, and a hand-wheel mounted in the bifurcated portion of the arm to allow reciprocatory movement of the drill carrier and to turn the same to accomplish adjustment of the drill carrier vertically through the feed nut to raise and lower the drill. 75

2. A drilling machine comprising a base, an upright carried by said base, an arm disposed from the upright to overhang the base and provided at its end with a bifurcated opening, a drill carrier mounted in conjunction with said arm to be capable of vertical reciprocatory movement, a feed nut received around said drill carrier, an operating lever pivotally mounted in its middle portion on the standard to be capable of swinging movement, fork arms carried by one end of said operating lever and engaged to transmit reciprocatory movement to said feed nut as the lever is rocked, means to rock the lever, and a hand wheel mounted in the bifurcated portion of the arm to allow reciprocatory movement of the drill carrier and to turn the same to accomplish adjustment of the drill carrier vertically through the feed nut to raise and lower the drill. 90

3. A drilling machine comprising a base, an upright mounted on said base, an arm carried by the upper end of said upright and provided on its free end with a bifurcated portion, a frame member mounted on the opposite side of the upright, a power shaft mounted near the lower end of the upright, a hand wheel mounted in the bifurcated portion of the arm, a drill carrier mounted in conjunction with said arm and said hand wheel to be capable of vertical reciprocatory movement and provided with screw-threads, a feed nut received on the screw-threaded portion of said drill carrier, 110 means to hold a drill secured with said drill carrier, an operating lever pivoted in its middle portion to the upright above the mounting of the power shaft, fork arms on said operating lever connected with said feed nut, a spring connected between the operating lever and the base to normally swing said lever in one of its paths of movement, an operating shaft carried by the frame member at a point adjacent the free 115

end of the operating lever, a driving connection from the power shaft to said operating shaft, and a cam carried by said operating shaft to swing the operating lever 5 against the tension of the spring and to release the same to permit return movement under the action of the spring.

In testimony whereof I affix my signature in presence of two witnesses.

JOSEPH BEAUDRY.
